Primary Examiner — Jack Reickel*Assistant Examiner* — Salamah Jordan(74) *Attorney, Agent, or Firm* — Clement Cheng(57) **CLAIM**

The ornamental design for a hexagonal trampoline with roof, as shown and described.

DESCRIPTION

FIG. 1 is an isometric view of a hexagonal trampoline with roof, showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the figures illustrate portions of the hexagonal trampoline with roof that form no part of the claimed design.
